BEER DISPENSER CABINET

Alfred A. Schroeder, San Antonio, Tex., assignor to Creative Vending Corporation, San Antonio, Tex., a corporation of Texas

Filed July 3, 1967, Ser. No. 7,694

Term of patent 14 years

(Cl. D94—3)

The figure is a front perspective view of a beer dispenser cabinet, showing my new design. The undisclosed side of the cabinet is the same in appearance as the side shown, and the rear is flat and plain.

I claim:

The ornamental design for a beer dispenser cabinet, as shown and described.
